(57) **CLAIM**

The ornamental design for a CATCH TRAINER as shown and described.

DESCRIPTION

FIG. 1 is a perspective view of a Catch Trainer showing the claimed design.

FIG. 2 is a front view of the Catch Trainer shown in FIG. 1, the back view being a mirror image thereof.

FIG. 3 is a left-side view of the Catch Trainer shown in FIG. 1, the right-side view being a mirror image thereof.

FIG. 4 is a top view of the Catch Trainer shown in FIG. 1.

FIG. 5 is a bottom view of the Catch Trainer shown in FIG. 1.

The dashed broken lines in the figures show portions of the Catch Trainer that form no part of the claimed design.
